UNITED STATES PATENT OFFICE.

EDWIN L. HILMER, OF HAGERSVILLE, PENNSYLVANIA.

TRAFFIC SIGNAL FOR AUTOMOBILES.

Application filed December 28, 1922. Serial No. 609,463.

To all whom it may concern:

Be it known that I, EDWIN L. HILMER, a citizen of the United States of America, residing at Hagersville, in the county of Bucks and State of Pennsylvania, have invented certain new and useful Improvements in Traffic Signals for Automobiles, of which the following is a specification.

This invention relates to improvements in traffic signals for automobiles, and has particular reference to that type of signal system wherein warning may be given of the driver's intention to turn to the right or left or stop.

An important object of the invention is to provide a signal system of the above mentioned character that will be effective to warn pedestrians and occupants of vehicles both in front and in the rear of the signaling machine in what particular direction such machine is about to travel.

A further object of the invention is to reduce the danger of collisions due to the unexpected changing of the direction or speed of travel of the vehicle.

A further object of the invention is to provide a signal for indicating the intention of the driver to turn either to the right or left to prevent collision, and further provide means for returning the signals to their normal position when the direction of travel of the vehicle has been changed.

Other objects and advantages will be apparent during the course of the following description.

In the accompanying drawings forming a part of this specification and in which like numerals are employed to designate like parts throughout the same,

Figure 1 is a vertical sectional view taken on line I—I of Fig. 2, and shows the casing employed to house the signal arms which form part of the invention.

Figure 2 is a vertical sectional view taken on line II—II of Fig. 1, and

Figure 3 is a horizontal sectional view taken on line III—III of Fig. 1.

Referring more in detail to the accompanying drawings, there is shown a casing 1, which is adapted to be attached one to either side of a vehicle, by the angle brackets 2, at a point near the rear of the same and is employed to house the signal arms used to indicate the intention of the driver to turn either to the right or left or to stop, and embodies a front wall 3, rear

wall 4, and inner side wall 5, the outer side is left open to allow for the projecting of the signal arms. The side wall 5 is provided with an opening 6 through which controlling cords, leading from a convenient position to the driver, pass into the casing to actuate the signalling apparatus housed therein. The outer side of the casing is left open, but is provided with a small door 7 which protects the operating mechanism associated with the signal arms, and is pivotally secured to the casing by the hinge 8 and held in its closed position by the clasp 9. The front and rear walls 3 and 4 respectively are formed with semi-circular projections 10 that are adapted to shield the outer illuminated portion of the signal arms when in their inoperative position.

Secured to the front and rear walls of the casing 1 is a shaft 11 that is adapted to have journaled thereto, as at 12, a signal arm 13 which increases in width as it approaches its outer end 14 to provide ample supporting means for the lamp housing 15 which may carry signal lamps between the lenses 17 that are preferably red in color and act as a stop signal. The inner end of the signal arm 13 is provided with a lever portion 18 which is provided with an aperture 19 to which an operating cord 20 is secured. Journaled to the shaft 11, as at 21, is a signal arm 22 that is similar in construction to the arm 13, being provided with an enlarged portion 14^a that is adapted to support a lamp housing 15^a to which are secured the lenses 17, the lenses carried by this arm being green in color. The inner end of the arm 22 is, likewise, provided with a lever portion 18^a having an aperture 19^a to which is secured a controlling cord 20^a.

Secured to the signal arm 22 and loosely mounted upon the shaft 11 is a substantially circular block 23 having a cam portion 24 that is shaped to form the shoulder 25. Secured to the top of the casing 1, as at 26, is a depending spring arm 27 having its free end bent to form the hook portion 28 which is adapted to engage the shoulder 25 formed on the cam portion 24 of the block 23, to hold the signal arm 22 when moved into the dotted line position as shown in Fig. 1. Journaled in the front and rear walls of the casing 1 is a shaft 29, having a crank portion 30 formed therein, a link 31 is loosely carried by the crank portion 30 and is connected at its opposite end to the hook portion 28 of

the spring arm 27. The crank portion 30 is further provided with a controlling cord 32 that should be extended to suitable means, not shown, the operation of which will move the spring arm 27 from engagement with the shoulder 25, to allow the signal arm 22 to return to its normal inoperative position within the casing 1.

The operation of the device is as follows:—

Should the operator of the vehicle desire to stop the same the flexible cords 20 connected to the stop signalling arms 13 are pulled upon for drawing the arms into their horizontal position to warn pedestrians and occupants of vehicles both in front and in the rear of the signalling machine. Should the driver desire to turn to the right, the cord 20^a connected to the signal arm positioned at the right side of the vehicle is pulled upon for moving that arm into its horizontal position. The spring arm 27 will engage the shoulder 25 that is associated with the signal arm 22, positioned upon the right side of the vehicle, for retaining the said arm in its signaling position. Upon operating the vehicle steering wheel to turn the front wheels in the proper direction to cause the vehicle to turn to the right, the cord 32 should be pulled upon. This movement of the cord 32 will exert a pull upon the crank portion 30 for moving the spring arm 27 out of engagement with the shoulder 25 for allowing the signalling arm to return to its vertical position within the casing 1. It will be apparent that the direction signalling arm 22, positioned upon the left side of the vehicle, may be similarly moved into its horizontal signalling position when the driver desires to turn his car to the left and that the cord 32 may be pulled upon to release this said signalling arm when the front wheels of the vehicle have been turned in the proper direction to cause the machine to turn to the left.

It is to be understood that the form of

my invention herewith shown and described is to be taken as the preferred example of the same, and that various changes in the shape, size, and arrangement of parts may be resorted to without departing from the spirit of the invention or the scope of the subjoined claims.

What is claimed as new is:—

1. In a signal of the class described, a casing having a closed upper end and having an outer side portion open, a shaft extending through said casing, a signal arm movable through the open side and having a cam constituting a hub and mounted eccentrically on said shaft, said cam having a latch shoulder formed thereon, a spring finger having one end fixed to the casing and its other end frictionally engaging the hub to check swinging of the arm in normal position, said finger engaging the shoulder to hold the arm raised upon movement of the arm to signalling position, means to actuate the arm, and means to move the finger off the shoulder to release the arm.

2. In a signal of the class described, a casing having a closed upper end and having an outer side portion open, a shaft extending through said casing, a signal arm movable through the open side and having a cam constituting a hub and mounted eccentrically on said shaft, said cam having a latch shoulder formed thereon, a spring finger having one end fixed to the casing and its other end frictionally engaging the hub to check swinging of the arm in normal position, said finger engaging the shoulder to hold the arm raised upon movement of the arm to signalling position, means to actuate the arm, a crank shaft journalled in the casing parallel to the first shaft, a link connecting said finger and the crank of the crank shaft, and means for actuating the crank shaft to cause movement of the finger away from the cam shoulder.

In testimony whereof I affix my signature.

EDWIN L. HILMER.
